(57) **CLAIM**

The ornamental design for a waterpark float, as shown and described.

DESCRIPTION

FIG. 1 is a front perspective view of the waterpark float.

FIG. 2 is a top view of the waterpark float.

FIG. 3 is a bottom view of the waterpark float.

FIG. 4 is an end view of the waterpark float.

FIG. 5 is side view of the waterpark float.

FIG. 6 is another end view of the waterpark float; and, FIG. 7 is another side view of the waterpark float.

The broken line showing of features of the waterpark float in FIGS. 1-2, and the broken-outlined bottom of the waterpark float in FIG. 3, are for the purpose of illustrating portions of Waterpark Float and forms no part of the claimed design.

1 Claim, 4 Drawing Sheets
